UNITED STATES PATENT OFFICE.

JOSEPH EASTWOOD, OF SAN FRANCISCO, CALIFORNIA.

HYDROCARBON-BURNER.

SPECIFICATION forming part of Letters Patent No. 680,573, dated August 13, 1901.

Application filed December 28, 1900. Serial No. 41,377. (No model.)

To all whom it may concern:

Be it known that I, JOSEPH EASTWOOD, a citizen of the United States, residing in the city and county of San Francisco and State 5 of California, have invented certain new and useful Improvements in Hydrocarbon-Burners; and I do hereby declare the following to be a full, clear, and exact description of the same.

10 My invention relates to that class of hydrocarbon-burners in which both air and steam are employed.

It consists in the relative arrangement of the several passages and their connections, 15 which I shall hereinafter describe.

The object of my invention is to provide a simple and effective burner of this class wherein the oil is prepared by the proper mingling of the steam therewith for the addition of the air at the moment of the exit of 20 all three fluids from the burner.

A further object is to provide an arrangement which shall enable the air as it passes through the burner to the point where it mixes 25 with the oil and steam to serve as a jacket to protect the parts of the burner from undue heat.

Referring to the accompanying drawings, Figure 1 is a longitudinal section of my 30 burner. Fig. 2 is a front view of its exit end.

A is a pipe forming a passage into the rear end of which, by means of a suitable connection, the oil-pipe B is adapted to feed the oil. Into said rear end the steam-pipe C, by means 35 of a suitable connection, is adapted to deliver steam, which mixes with the oil, and both are forced forward through said pipe or passage A to its contracted exit a. Around pipe A is a pipe D of sufficiently greater diameter 40 to leave an annular passage d. Into the rear end of this passage d, by means of a suitable connection, the air-pipe E is adapted to deliver air. As will be seen, the pipe D has a length sufficient to cause the annular air- 45 passage d to extend to and terminate substantially in the plane of the exit a of passage A. In practice the oil, steam, and air are supplied under pressure, each being separately controlled by a suitable cock, as shown. 50 This control enables the operator to supply more or less steam or air, according to the degree of heat required or the place of its

application. Thus by increasing the steam the flame may be lengthened to apply the heat at a desired point, and by increasing the air 55 the greatest heat may be had close to the exit of the burner. As the air is mingled with the oil and steam only at the exit of the latter, the long circumscribing passage d through which it flows enables it to serve as a jacket- 60 protector for the inner pipe, through which the oil and steam pass, thereby keeping the latter from getting too hot; and, further, the air also protects the outer pipe from undue heat, and as said pipe is no longer than the 65 inner pipe the outer pipe is protected throughout its entire length and will not melt away, as would be the case if it projected beyond the exit of the oil and steam. The burner is thus prevented from getting hot. The oil 70 and steam are well mixed in the inner passage and are ready at their exit for the air which is supplied from the surrounding air- passage.

Having thus described my invention, what 75 I claim as new, and desire to secure by Letters Patent, is—

1. In a hydrocarbon-burner, the combination of an inner tube open at its rear end, an oil-supply nozzle directed axially into the extreme rear open end of said tube, of a size to leave a passage between the same and the walls of the tube, a chamber connected to the rear end of said tube, a steam-supply entering said chamber directly in rear of said oil- 80 nozzle and in line therewith, a tube surrounding said inner tube and connecting at its rear with an air-supply, said surrounding tube being so disposed as to deliver air into the mingled oil and steam as they issue from the inner tube, substantially as described.

2. In a hydrocarbon-burner, the combination of an inner tube open at its rear end, a chamber connected to the rear end of said tube, an oil-nozzle connected with an oil-sup- 85 ply and projecting axially into and terminat- 90 ing in the extreme rear open end of said tube, of a size to leave a passage between the same and the walls of the tube, a steam-nozzle enter- 95 ing said chamber axially in rear of and in line with said oil-nozzle, a chamber surround- 100 ing said inner tube at the rear, an air-supply connected therewith, and an outer tube connected to said surrounding chamber and sur-

rounding said inner tube, substantially as described.

3. In a hydrocarbon-burner, the combination of an inner tube open at both ends, a chamber secured to and surrounding the rear open end of said tube, an oil-pipe entering said chamber and having a nozzle extending longitudinally into the rear end of said tube, of a size to leave a passage between the same and the walls of the tube, a steam-pipe having a nozzle extending into the rear end of said chamber directly behind and in line with said oil-nozzle, an outer tube surrounding

said inner tube, a second chamber surrounding and secured to said tube and separated from said first-mentioned chamber with which second chamber said outer tube connects, and an air-supply pipe connecting with said second chamber, substantially as described.

In witness whereof I have hereunto set my hand.

JOSEPH EASTWOOD.
